AUTOMOBILE GRILLE

Frederick Reynolds, Bloomfield Hills, Mich., assignor to Chrysler Corporation, Highland Park, Mich., a corporation of Delaware

Application July 15, 1954, Serial No. 31,444

Term of patent 7 years

(Cl. D14—18)

Fig. 1 is a perspective view of an automobile grille, wherein the broken lines indicating an automobile are for illustrative purposes only;

Fig. 2 is a front elevational view of an automobile grille showing my new design;

Fig. 3 is an enlarged fragmentary front elevational view thereof;

Fig. 4 is a fragmentary plan view of the automobile grille illustrated in Fig. 3; and

Figs. 5, 6, 7, 8, 9 and 10 are sectional views taken on the lines 5—5, 6—6, 7—7, 8—8, 9—9 and 10—10 respectively of Fig. 3.

The characteristic features of my design reside in the portions shown by means of full lines in the drawings.

I claim:

The ornamental design for an automobile grille, substantially as shown and described.
